US00D939709S

(12) **United States Design Patent** (10) **Patent No.:** **US D939,709 S**
Wingo et al. (45) **Date of Patent:** **** Dec. 28, 2021**

(54) **X-RAY DEVICE FOR UNMANNED AERIAL VEHICLES**

(71) Applicant: **Talon Aerolytics (Holding), Inc.**, West Point, GA (US)

(72) Inventors: **Austin Wingo**, Opelika, AL (US); **Timothy Dunnigan**, Lanett, AL (US); **Phillip Bevel**, Opelika, AL (US); **Eric Hare**, Opelika, AL (US); **Timothy Dunnigan, Jr.**, Auburn, AL (US)

(73) Assignee: **Talon Aerolytics (Holding), Inc.**, West Point, GA (US)

(**) Term: **15 Years**

(21) Appl. No.: **29/724,833**

(22) Filed: **Feb. 19, 2020**

CLAIM

The ornamental design for an X-ray device for unmanned aerial vehicles, as shown and described.

DESCRIPTION

FIG. 1 is a perspective view of an X-ray device for unmanned aerial vehicles showing our new design;

FIG. 2 is a top plan view thereof;

FIG. 3 is a left elevation view thereof; and,

FIG. 4 is a bottom plan view thereof.

The broken line shown in the drawings are for the purpose of illustrating environment and form no part of the claimed design.

1 Claim, 4 Drawing Sheets
